CLAIM

The ornamental design for a pet tracker packaging, as shown and described.

DESCRIPTION

FIG. 1 is a top perspective view of a pet tracker packaging in accordance with the disclosed subject matter.

FIG. 2 is a front plan view of the pet tracker packaging shown in FIG. 1.

FIG. 3 is a back plan view of the pet tracker packaging shown in FIG. 1.

FIG. 4 is a right side view of the pet tracker packaging shown in FIG. 1.

FIG. 5 is a left side view of the pet tracker packaging shown in FIG. 1.

FIG. 6 is a top plan view of the pet tracker packaging shown in FIG. 1.

FIG. 7 is a bottom plan view of the pet tracker packaging shown in FIG. 1.

FIG. 8 is a top perspective view of the bottom cover of the pet tracker packaging shown in FIG. 1, with the top cover (not shown) being identical to the bottom cover.

FIG. 9 is a front plan view of the bottom cover shown in FIG. 8.

FIG. 10 is a back plan view of the bottom cover shown in FIG. 8.

FIG. 11 is a right side view of the bottom cover shown in FIG. 8.

FIG. 12 is a left side view of the bottom cover shown in FIG. 8.

FIG. 13 is a top plan view of the bottom cover shown in FIG. 8.

FIG. 14 is a bottom plan view of the bottom cover shown in FIG. 8.

FIG. 15 is a top perspective view of the middle tray of the pet tracker packaging shown in FIG. 1.

(Continued)

FIG. 16 is a front plan view of the middle tray shown in FIG. 15.
 FIG. 17 is a back plan view of the middle tray shown in FIG. 15.
 FIG. 18 is a right side view of the middle tray shown in FIG. 15.
 FIG. 19 is a left side view of the middle tray shown in FIG. 15.
 FIG. 20 is a top plan view of the middle tray shown in FIG. 15.
 FIG. 21 is a bottom plan view of the middle tray shown in FIG. 15.
 FIG. 22 is an exploded top perspective view of the pet tracker packaging shown in FIG. 1, showing the top cover, middle tray, and bottom cover.
 FIG. 23 is a top perspective view of the bottom cover shown in FIG. 8, showing the bottom cover accommodating a pet tracker attachment system as depicted by broken lines; and, FIG. 24 is a top perspective view of the middle tray shown in FIG. 15, showing the middle tray accommodating a pet tracker as depicted by broken lines.
 The broken lines showing of pet tracker and pet tracker attachment in FIGS. 23 and 24 are included for the purpose of illustrating environmental structure while all other broken lines illustrate portions of the pet tracker packaging; the broken lines form no part of the claimed design.
